IRONING TABLE TOP

John R. Lucas, Columbus, Ind., assignor to Arvin Industries, Inc., Columbus, Ind., a corporation of Indiana Filed Mar. 6, 1963, Ser. No. 263,323 4 Claims. (Cl. 103—77)

This invention relates to an ironing table top and more particularly to an ironing table top having an expandable nose.

It is an object of my invention to provide an ironing table top which can be adjusted to provide its nose portion with a tapered or a generally rectangular configuration, which can be quickly and easily adjusted to provide either of said configurations, which can be economically manufactured largely from inexpensive sheet-metal, and which will prove sturdy and durable in use.

According to one form of my invention, there is provided an ironing table top having a depending border skirt and consisting of a main body portion with parallel lateral edges continuous with a nose portion having converging lateral edges which give said nose tapered configuration. Swingably connected to the lateral edges of the nose portion are a pair of generally triangularly shaped wings swingable between an extended position in which they are generally coplanar with the upper face of the top and their lateral edges form a substantial rectilinear continuation of the lateral edges of the body portion and a retracted position in which they are disposed under and within the lateral extent of the nose portion.

Each of said wings is swingably connected by link means to a pivot plate carried under the nose portion. The pivot plate is rotatable about an axis normal to the plane of said top. As said plate is rotated in one direction, said link means will swing the wings upwardly and outwardly into their extended position. Conversely, rotation of the plate in the opposite direction will cause said link means to swing the wings downwardly and inwardly into their retracted position in which they are disposed within and below the lateral extent of the nose portion.

Other objects and features of the invention will become apparent from the more detailed description which follows and from the accompanying drawings, in which:

FIG. 1 is a plan view of an ironing table top embodying my invention;

FIG. 2 is an enlarged fragmentary bottom plan view of the nose portion of the ironing table top shown in FIG. 1;

FIG. 3 is a vertical section taken on the line 3—3 of FIG. 2;

FIG. 4 is an enlarged fragmentary vertical section taken on the line 3—3 of FIG. 2, but showing the nose portion in its retracted position; and

FIG. 5 is a fragmentary vertical section taken on the line 5—5 of FIG. 2.

A conventional ironing table comprises a top 10 supported on a pair of ground-engaging legs 12. Said top has a planar upper face and is provided with the peripherally extending border skirt 14. The top includes a body portion 15 having parallel longitudinally extending lateral edges 16. One end of the body portion 15 is continuous with a nose portion 17 whose lateral edges converge inwardly from the body portion 15 to thus give said nose portion a tapered configuration.

It is frequently desirable for the ironing table top to have a uniform width through its length so that the lateral edges 18 of the nose portion are disposed in longitudinal alignment with the lateral edges 16 of the body portion 15. To this end, I provide a pair of generally triangularly shaped wings 20 and 21 conveniently formed from sheet-metal, and each having a downwardly projecting flange 22

2

along its inner edge and a stiffening bead 24 extending around its other edges. A plurality of hinges 26 are mounted on the wing flanges 22 and the top skirt 14 within the longitudinal extent of the lateral edges 18 of the nose portion 17. The wings 20 and 21 are swingable about the hinge axes parallel with the plane of the top from a retracted overlapping position in which they are disposed wholly within the lateral extent of the nose portion 17 and an extended operative position in which they project laterally from said nose portion and are disposed in generally coplanar relationship with the upper surface of the top. In such extended position, the outwardly presented edges of the wings are in substantial longitudinal alignment with the lateral edges 16 of the body portion 15 to thus give the top 10 a substantially uniform width throughout its entire length. As is best shown in FIG. 4, the axes of the hinges are disposed intermediate the depth of the top skirt 14, and the wing flanges 22 have depths equaling about one-half the skirt depth. In this manner, the flanges will substantially abut the skirt 14 when the wings are extended and the wings are free to be swung into a fully retracted position below the nose portion 17.

As shown in the drawings, the wings are swingable between their retracted and extended position by an adjusting mechanism mounted on the wings and on a base plate 27 mounted on the underside of the nose portion 17. A pivot plate 28 is rotatably interconnected to the top 10 in parallelism therewith by a pivot pin 30 mounted in the pivot plate 28 and received in a downwardly struck offset 31 in the base plate 27. As shown, the pin 30 is normal to the plane of the top 10 and the offset 31 is in sliding face-to-face engagement with the plate 28 adjacent said pin 30. Conveniently, a downwardly projecting handle 33 is mounted on the plate 28 to facilitate rotation thereof. A pair of brackets 34 are rotatably mounted on the underside of the wings 20 and 21 by pins 36. The brackets 34 are connected to a pair of arcuate rods 38 by pivot pins 39. The opposite end of the rod 38 interconnected to the wing 21 is connected by a pivot pin 40 to a downwardly projecting bracket 42 mounted adjacent one end of the plate 28 by a pivot pin 43, and the opposite end of the rod 38 interconnected to the wing 20 is connected by a pivot pin 40 to a downwardly projecting bracket 44 mounted adjacent the opposite end of the plate 28 by a pivot pin 45. The pivot pins 43 and 45 form pivot axes parallel to the axis of the pin 30, and the pin 43 is disposed slightly closer to the pin 30 than the pin 45. As shown, a downwardly projecting annular offset 46 in the plate 27 is radially spaced from the offset 31 to engage the pins 43 and 45 for stabilizing the plate 28 against wobbling during its rotation.

To move the wings 20 and 21 from their retracted positions shown in FIG. 4 to their extended positions shown in FIG. 3, the plate 28 is rotated from its dotted line position to its full line position. During such rotation, the brackets 42 and 44 will rotate about their pivots 43 and 45, respectively, and the brackets 34 will rotate about their pivots 36. The links will swing about their connections to the brackets 34 and 42 and 44 to thus cause the wings 20 and 21 to swing through arcs of about 180° until they are disposed in coplanar relationship with the upper face of the nose portion 17. As shown in FIG. 2, as the plate 28 is rotated in a wing-extending direction, the pin 43 and its associated link 38 swing past center at point A and the pin 45 and its associated link 38 swing past center at point B, the pin 45 swinging slightly farther past center than pin 43. With the pins 43 and 45 and links 38 being disposed over center when the wings are fully extended, the wings will be braced in their extended positions. As will be apparent from FIG. 3, the wings are also braced in extended position by the leaves of the hinges 26 being

disposed in folded abutting relationship. Conveniently a pair of fingers 50 are mounted on the plate 27 to engage the links 38 to limit swinging movement of the plate 28 in its wing-extending position.

To move the wings to their retracted positions, the plate 28 is moved in a clockwise direction as viewed in FIG. 2. Since the pin 45 swings farther past center than the pin 43, the wing 21 will start to swing downwardly before the wing 20 so that wing 20 will overlap wing 21 in retracted position. As the plate 28 is rotated in its wing-retracting direction, the brackets 42 and 44 will again rotate about their pivots 43 and 45 and the brackets 34 will rotate about their pivots 36. The links 38 swing about their connections to said brackets to pull the wings 20 and 21 downwardly and inwardly through arcs of approximately 180° until said wings are disposed in the dotted line position illustrated in FIG. 2. The frictional engagement of the several parts of the wing extension and retraction mechanism is sufficient to releasably retain the wings in their retracted overlapping position and thus prevent them from swinging downwardly when the top 10 is in its normal horizontal position.

I claim:

1. In combination with an ironing table top having a body portion with parallel lateral edges and a nose portion extending integrally from one end of said body portion and having converging lateral edges,

(a) a pair of wings swingably connected to the opposed lateral edges of said nose portion on axes parallel to said top,

(b) a pivot plate rotatably interconnected to the underside of said nose portion on an axis normal to said top and disposed within the lateral extent of said nose portion, and

(c) a pair of links swingably interconnected to said pivot plate and said pair of wings whereby upon movement of said pivot plate in one direction said links will swing said wings into an extended position in which they are coplanar with said top and their outwardly disposed lateral edges are in substantial longitudinal alignment with the lateral edges of the body portion and upon movement of said pivot plate in an opposite direction said links will swing said wings into a retracted position in which they are disposed below and within the lateral extent to said nose portion, and

(d) said links being interconnected to said pivot plate at different distances from the axis of said pivot plate whereby the wing interconnected to the link interconnected closer to the pivot plate axis will start toward its retracted position prior to the other wing during wing retraction to permit said wings to be in overlapping relationship in retracted position.

2. In combination with an ironing table top having a body portion with parallel lateral edges and a nose portion extending integrally from one end of said body portion and having converging lateral edges,

(a) a pair of wings swingably connected to the border

skirt along the opposed lateral edges of said nose portion on axes parallel to said top,

(b) a pivot plate rotatably interconnected to the underside of said nose portion on an axis normal to said top and disposed within the lateral extent of said nose portion,

(c) a first pair of brackets rotatably mounted on said pivot plate on axes normal to said top and at different distances from the axis of said pivot plate,

(d) a second pair of brackets rotatably mounted on said wings on axes normal to the planes of said wings, and

(e) a pair of links swingably connected at their opposite ends to said first and second pairs of brackets on axes parallel with said top whereby upon movement of said pivot plate in one direction said links will swing said wings into an extended position in which they are coplanar with said top and their outwardly disposed lateral edges are in substantial longitudinal alignment with the lateral edges of the body portion and upon movement of said pivot plate in an opposite direction said links will swing said wings into a retracted position in which they are disposed below and within the lateral extent of said nose portion,

(f) said plate upon movement in a wing-extending direction swinging said first pair of brackets past a position in which said links disposed said wings in a coplanar relationship with the top and whereby the wing interconnected to the brackets of said first pair of brackets spaced closer to the pivot plate axis will start toward its retracted position prior to the other wing during wing retraction to permit said wings to be in overlapping relationship in retracted position.

3. The invention as set forth in claim 2 with the addition that,

(a) a peripheral border skirt extends downwardly from said top, and

(b) said pair of wings have depending flanges along one of their edges,

(c) said flanges having a depth substantially less than the depth of said border skirt and swingably connected to said border skirt within the extent of said nose portion on axes intermediate the depth of said border skirt and parallel with said top.

4. The invention as set forth in claim 1 in which

(a) means are provided on said top to limit the swinging movement of said links in a wing-extending direction.
